SPECTACLE CASE

Joan L. Foss, Rochester, N. Y., assignor to Bausch & Lomb Optical Company, Rochester, N. Y., a corporation of New York

Application June 3, 1953, Serial No. 25,300

Term of patent 14 years

(Cl. D57—1)

To all whom it may concern:

Be it known that I, Joan L. Foss, a citizen of the United States and a resident of Rochester, county of Monroe, and State of New York, have invented a new, original, and ornamental Design for a Spectacle Case, of which the following is a specification, reference being had to the accompanying drawing, forming a part hereof.

Fig. 1 is a front elevational view of a spectacle case, showing my design.

Fig. 2 is a rear elevational view thereof.

Fig. 3 is a front view of the spectacle case with the cover in open position.

Fig. 4 is a rear view of same.

I claim:

The ornamental design for a spectacle case, substantially as shown.

JOAN L. FOSS.
